Primary Examiner — Robert Delehanty(74) *Attorney, Agent, or Firm* — Foley & Lardner LLP(57) **CLAIM**

I claim the ornamental design for a faucet, as shown and described.

DESCRIPTION

FIG. 1 is a top, front, right perspective view of an embodiment of the claimed design,

FIG. 2 is a front elevation view thereof,

FIG. 3 is a rear elevation view thereof,

FIG. 4 is a left elevation view thereof,

FIG. 5 is a right elevation view thereof,

FIG. 6 is a top, plan view thereof; and,

FIG. 7 is a bottom, plan view thereof.

The ornamental design which is claimed is shown in solid lines in the drawings. The broken lines in the drawings form no part of tile claimed design. Broken lines formed by equal length dashes show unclaimed subject matter. Broken lines formed of unequal length dashes (i.e., dash-dot) define bounds of the claimed design. Broken away symbols having a jagged element show that no particular length of tile portion is claimed.
